UNITED STATES PATENT OFFICE.

JOHN FIELDEN KING, OF KALISPELL, MONTANA.

AWNING-ROLLER CONSTRUCTION.

1,424,572.

Specification of Letters Patent. Patented Aug. 1, 1922.

Application filed September 27, 1920. Serial No. 413,122.

To all whom it may concern:

Be it known that I, JOHN F. KING, a citizen of the United States, residing at Kalispell, in the county of Flathead and 5 State of Montana, have invented certain new and useful Improvements in Awning-Roller Constructions; and I do declare the following to be a full, clear, and exact description of the invention, such as will enable others skilled in the art to which it appertains to make and use the same.

This invention relates to improvements in roller structures, and it has particular reference to the construction of awning rollers.

15 One object of the invention is to provide an awning roller having a longitudinally extending central bar or rod carrying disks at its center and adjacent its ends and having truss rods carried by these disks, each 20 truss rod having its intermediate portion engaged by the center disk and offset circumferentially of the roller with respect to its end portions thus causing the roller to be braced in a very efficient manner when strain 25 is applied when rolling an awning upon the roller.

Another object of the invention is to so construct this roller that the end portions of the rods may be firmly held in engagement with the end disks and the end portions of the truss rods prevented from dragging out of engagement with the end disks when the center disk is turned to offset the 30 intermediate portions of the truss rods with respect to the end portions thereof.

Another object of the invention is to provide an awning roller which can be very readily assembled and which when assembled will be very strong and durable and 35 not liable to bend when in use.

Another object of the invention is to so construct this roller that the truss rods may be mounted in notches cut in the outer peripheral portions of the disk carried by the 40 center shaft thus permitting of the rods being easily and quickly put in place or removed when desired.

Another object of the invention is to so construct this roller that when assembled, 45 the portions of the truss rods between the center disk and end disks will extend in crossed relation and thus permit the truss

rods to brace the roller longitudinally and circumferentially.

Another object of the invention is to provide an improved awning roller of the above 55 mentioned type which is such that it may be used to replace the ordinary awning rollers now on the market, thus permitting the usual wooden supporting roller to be dispensed with.

Other objects and advantages of the invention will be apparent during the course of the following description.

In the accompanying drawings forming a 65 part of this specification and in which like numerals are employed to designate like parts throughout the same:

Figure 1 is a perspective view of a roller 70 constructed in accordance with my invention.

Figure 2 is a transverse section taken on the line 2—2 of Fig. 1.

Figure 3 is a perspective view of the parts 75 of the rollers disconnected.

In carrying out my invention, I make use of a sleeve or casing in which I place a reinforced rod, the latter being reinforced by novel bracing means which is such that it transfers the weight which is exerted on the center of the rod, to the opposite ends thereof, thus equalizing the pull and preventing bending of said rod between its ends as 80 ordinarily occurs.

Referring to the drawings, wherein the preferred embodiment of my invention is clearly illustrated, it will be seen that the numeral 1 designates a tubular member made from suitable material in which the rod 2 above referred to is disposed. This 85 tube 1 and rod 2 will extend for the entire length and slightly beyond the opposite sides of the awning to permit them to be rotatably mounted in the ordinary brackets which are employed for supporting the awning. Arranged on rod 2, one at each end and one between its ends, are a plurality of heads 3 in the form of collars, the same being secured in position by means of set-screws or the like.

4. Examination of these heads will disclose the fact that the periphery of each one is provided with a plurality of spaced notches 5, the notches of the respective heads being preferably in longitudinal alignment with

one another. The bracing means above referred to is associated with these notches. This bracing means is preferably in the form of a plurality of truss-rods 6, these truss-rods being provided at their opposite ends with reduced necks 7 seated in notches in the respective end heads which are in longitudinal alignment with one another, the central portions of these truss-rods being seated in notches in the central head 3 which are circumferentially out of longitudinal alignment with the notches that the ends of the respective truss-rods are seated in. It is to be noted that on the extremity of each of the truss-rods, enlargements constituting heads 8 are formed for the purpose of better retaining the truss-rods in the mountings. Also, the faces of the heads 3 have annular grooves or channels 9 formed therein in which the headed ends of said truss-rods seat to prevent accidental disconnection of the truss-rods from the heads 3. Any suitable means, such as turn-buckles 10 may be employed for shortening or lengthening the truss-rods. By arranging the central portions of the various truss-rods in notches in the central heads 3 which are circumferentially out of alignment with the notches in which the opposite ends of the truss-rods are seated and connected, it will be seen that the truss-rods become bowed and cross one another and provide an extremely strong and durable structure. Hence, with this construction, when weight is exerted on the central portions of rod 2, the mechanical connection of the truss-rods with the heads adjacent the ends of this rod will transfer the weight or pull to the opposite ends of this rod 2 and will thus equalize and uniformly distribute, to a very great extent, the pull exerted on this rod. In this way possible bending of the rod between its ends, as it ordinarily does, is prevented.

From the foregoing description, it will be seen that I have devised an extremely advantageous and novel awning roller construction which can be sold as an attachment and may be used to replace the old awning rollers now on the market, which type of rollers, as before stated, necessarily have small wooden supporting rollers arranged at points between their ends for the purpose of preventing bending of the roller at these points. With my roller, these wooden supporting rollers just referred to, can be entirely eliminated. Consequently, less wear and tear of the canvas awning is caused when my improved roller is in use than with the ordinary construction and arrangement. Furthermore, I so construct my roller that it is adapted to be easily and readily mounted for rotation in the ordinary bearings provided with the usual supporting brackets and at this point I may state that, if desirable, the peripheral portions of the heads 3

referred to in the foregoing description may be further provided with sockets for reception of ball bearings which may be used in mounting my roller in the usual bearings. The employment of a plurality of truss-rods 70 arranged spirally in the manner shown insures that no matter what position the rod 2 is in, the pull caused by the weight exerted on the center of this rod will be transferred to the ends thereof for the purpose of equalization of pull. Consequently, the construction and arrangement I employ insures effectiveness in preventing bending of the roller between its ends as ordinarily occurs. 75

A careful consideration of the foregoing 80 description taken in connection with the accompanying drawing, will enable persons skilled in the art to which this invention appertains, to obtain a clear understanding of the same, therefore, further description is 85 deemed unnecessary.

Advantageous and effective results, can no doubt, be obtained with the construction and arrangement of parts shown and described. For this reason, this construction 90 and arrangement is taken as the preferred embodiment of my invention. However, I wish it to be understood that various minor changes in the size, shape and arrangement of parts may be resorted to without departing 95 from the spirit of the invention or the scope of the subjoined claims.

I claim:

1. A device of the class described comprising a central rod provided at its opposite ends and intermediate its ends with heads, and a plurality of truss-rods secured at their opposite ends to said end heads and connected at their centers to the remaining head, the points of connection of said truss rods with the respective heads being the same radial distance from said central rod, the central point of connection of each rod being disposed out of circumferential longitudinal alignment with respect to the end points of connection, whereby the rods are caused to cross one another. 100

2. A device of the class described comprising a rod, collars arranged thereon near the ends and at a point between the ends, 115 the peripheries of said collars being provided with notches, and a plurality of adjustable truss-rods having their ends removably seated in the notches in the end collars and having their central portions 110 seated in notches in the central collar which are circumferentially out of longitudinal alignment with respect to the notches in which their opposite ends are seated and secured. 120

3. In a roller structure, a tube, a rod arranged therein, collars on the rod, one at each end and one at the center, the periphery of each collar being notched and there being annular grooves formed in the outer 130

faces of the end collars, and a plurality of longitudinally adjustable truss-rods provided at their ends with heads arranged in said grooves, and adjacent said heads with reduced necks removably seated in the notches in the end heads, the central portions of the truss-rods being seated in

notches in the central head which are out of circumferential longitudinal alinement with respect to the notches in the end collars in 10 which their opposite ends are seated.

In testimony whereof I have hereunto set my hand.

JOHN FIELDEN KING.
